Primary Examiner — Marie D. Fast Horse(74) *Attorney, Agent, or Firm* — NSIP Law(57) **CLAIM**

I claim the ornamental design for a router, as shown and described.

DESCRIPTION

FIG. 1 is a front perspective view of a router showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 1;

FIG. 9 is an enlarged view of the encircled portion in FIG. 4; and,

FIG. 10 is an enlarged view of the encircled portion in FIG. 4.

The broken lines in the figures depict portions of the router which form no part of the claimed design.

The dot-dash broken lines encircling portions of the claimed design that are illustrated in enlargements form no part of the claimed design.

1 Claim, 8 Drawing Sheets(56)
